SHEET FEEDING MECHANISM

Franklin E. Curtis, Willoughby, Ohio, assignor to
Addressograph-Multigraph Corporation, Cleve-
land, Ohio, a corporation of Delaware

Application February 8, 1941, Serial No. 378,034

5 Claims. (Cl. 209—88)

This invention relates to improvements in sheet delivery mechanisms, and is especially concerned with improvements in and relating to sheet feeding mechanisms which are especially adapted to feed sheets one at a time to another mechanism, such as a printing or duplicating machine.

The general object of the present invention is to provide an improved sheet feeding mechanism which will remove sheets one at a time from the top of a stack or pile of sheets and deliver them to and in timed relationship with another mechanism, such as a printing machine.

Another object of the present invention is to provide an improved sheet feeding mechanism, which will effectively feed sheets from a stack to a printing machine at a relatively high rate of speed and at the same time prevent superposed sheets from reaching the printing machine.

Another further object of the invention is to provide an improved sheet detecting and diverting mechanism for a sheet feeder which mechanism will detect the presence of superposed sheets and divert such sheets from the normal path of sheet delivery.

Other objects and features of this invention will become more apparent from the following description, reference being had to the accompanying drawings in which there is illustrated a preferred embodiment of the invention. The essential features of the invention will be summarized in the claims.

In the drawings, Fig. 1 is a plan partly broken away of a machine for separating and delivering sheets from the top of the stack thereof, incorporating the mechanism of this invention for preventing the delivery of multiple sheets; Fig. 2 is an enlarged sectional view of the sheet separating and feeding mechanism; Fig. 3 is an enlarged sectional detail of the sheet separating mechanism; Fig. 4 is a sectional detail of a sheet deflector; Fig. 5 is an enlarged sectional detail of a sheet detector or gauge unit, the plane of the section being indicated by the line 5—5 on Fig. 6; Fig. 6 is a front elevation of the unit illustrated in Fig. 5; Fig. 7 is a horizontal sectional detail as indicated by the lines 7—7 on Fig. 5.

Referring now to the drawings, wherein there is illustrated a preferred form of the invention, and particularly to Figs. 1 and 2, there is shown a portion of the general frame of a paper feeding machine having my invention. The frame portion shown comprises a suitable support 10 and a pair of parallel upright plates 11 braced by

suitable cross bars hereinafter mentioned. This frame carries a suitable sheet separating device which separates the top sheet from the pile and progresses it to suitable delivery means from which it may pass to a printing machine not shown.

The present invention is especially concerned with a detector unit indicated generally at 18 coacting with one of the feed rolls and controlling the operation of a deflector plate 19 which intercepts and diverts superposed sheets before they reach the delivery tapes which may lead to a printing machine. Such printing machine may be of any suitable form and may be located and connected as shown in my Patent 2,293,046, issued August 18, 1942, to my assignee Addressograph-Multigraph Corporation, as a division of the present application.

The paper table which supports a pile or stack 20 of sheets W to be fed, is illustrated in Figs. 1 and 2. As there shown, the stack of sheets W is placed on a table 45, with its forward corners seated in vertically extending guides 44 which are adjustable transversely. The paper table 45 is slidably mounted for vertical movement in the frame 10, the arrangement being such that the table may be raised at periodic intervals to maintain the uppermost sheet in the stack substantially in a predetermined plane where it may be conveniently engaged by the sheet separating mechanism hereinafter to be more fully described.

The paper table 45 is shown as provided with a pair of side flanges 46, each of which carries a pair of rollers 47. These rollers project outwardly from the sides of the table 45 and engage the flanges of vertically extending channels 48 carried by the frame 10, thus guiding the table for vertical movement.

The table 45 is supported by a pair of chains, one of which is shown at 50 in Fig. 2. These chains are attached to respective side flanges 46 of the table 45 as at 51, and extend upward to respective sprocket wheels 52 and thence downward. Counterweights 55 are secured to the depending free ends of each chain. The sprocket wheels 52 are secured to a cross shaft 56 which is journaled in the side plates 51 supported by the frame 10. This shaft is operated by any suitable mechanism to move the table and retain it in an adjusted position.

The paper table 45 is periodically raised by power mechanism actuating the shaft 56. The operation of this power mechanism is controlled by the location of the top of the stack. This is

effected through the instrumentality of a ball 70 resting on the top of the stack and adapted whenever the ball descends a predetermined amount to initiate the raising mechanism. Any suitable mechanism may be employed for this purpose, for instance, that shown in my prior Patent 2,358,560, granted September 19, 1944, to my assignee Addressograph-Multigraph Corporation as a division of this application. It may be noted also that in practice the ball 70 is suitably linked with the printing mechanism to which the paper is fed so that the ball may be periodically moved out of contact with the top sheet preceding the feeding of such sheet.

The sheet separating and feeding mechanisms which are best illustrated in Figs. 2 and 3, will now be described. The separation of the top sheet W from the stack is accomplished by a suction foot 110. This foot is lowered into contact with the top sheet, suction applied, drawing the sheet into contact with the lower end of the foot, whereupon the foot is raised, moving a short distance rearwardly while raising, and then moved in a substantially forward direction to insert the separated sheet between feed rolls 111 and 112. As the sheet is inserted into the bite of these rolls, the suction is released and the rolls continue the feeding of the sheet. After the rolls have completed the feeding of the sheet, the suction foot 110 is lowered into contact with the next sheet on the stack and the cycle of operation is repeated.

The suction foot 110 comprises a hollow casting, the lower end of which is open, and the upper end of which is connected by a flexible conduit 115 and other means hereinafter to be described as a motor driven vacuum pump, not shown. This foot 110 is adjustably secured to a shaft 116 by a set screw 117 to facilitate adjustment transversely of the feeding mechanism.

The suction foot is operated in timed relation with the printing machine. As illustrated in Fig. 2, the shaft at 116 carrying the suction foot is journaled at its ends in a pair of cross arms 113 which are secured to a cross shaft 118 rotatably mounted in the side plates 57. As illustrated in Fig. 3, the shaft 118 has secured to its outer end a depending lever 119 and this lever may be suitably linked with the printing machine.

The rocking of the lever 119, thus results in the rocking of the shaft 118 and imparts a rocking movement to the foot carrying shaft 116. As heretofore mentioned, the suction foot first raises, moving slightly rearwardly as it does, and then swings forward to move the sheet to the bite of the feed rolls 111 and 112. This operation and movement is best illustrated in Fig. 3. As there shown, an arm 125 is secured to the foot carrying shaft 116 and is provided at its lower end with a roller 126 which is drawn by a spring 128 into engagement with a guide plate 127 secured to a side plate 57. This guide plate (Fig. 3) inclines upwardly and rearwardly so that as the shaft 118 and arms 113 rock in a clockwise direction (Fig. 3) the lower end of the suction foot moves upward and rearward, as indicated by the progressive series of dotted lines 129. When the foot 110 reaches the position indicated by the uppermost of these lines, a second roller 130, carried by the arm 125 is engaged by a stationary abutment 131. Continued rocking of the parts about the shaft 118 then causes the suction foot to swing in a clockwise direction about the moving axis of the shaft 116, moving the foot toward the bite of the feeding rolls as 75

indicated by the series of dotted lines 132. This movement of the suction foot has been found to be highly efficient in separating the top sheet from the stack and enables the feeding of sheets of various thicknesses at relatively high speeds.

To assist in the separation of the sheets, I provide a transversely extending frame bar 133 located at the front edge of the stack and carrying one or more flat spring fingers 136. This finger or fingers are adjustably positioned on the bar 133 by adjusting screw 138. Each finger 136 is normally spaced a predetermined distance above the uppermost sheet W of the stack and above the lowermost position of the sheet engaging the bottom surface of the suction foot. It will be noted from Fig. 3, that these spring fingers project inwardly above the stack, but a comparatively short distance, hence, as the suction foot raises a sheet W from the stack, the innermost end of the sheet is drawn with a wiping motion past the end of the finger. Should two or more sheets tend to raise with the suction foot, this wiping movement generally causes all but the top sheet to return to the stack.

A suitable motor driven pump not shown provides the suction supply for the foot 110. The suction side of the pump is connected with a valve 145 by a conduit 144. The valve is connected with the suction foot by the flexible conduit 115. The suction foot 110 is controlled by opening the valve 145 to atmospheric pressure. The valve 145 is best shown in Fig. 2, and comprises a valve body having a through passageway 146, the opposite ends of which are in communication with the conduits 115 and 144 respectively. Intermediate its ends the valve body is provided with a port 147, which when closed, brings the suction side of the pump into direct communication with the suction foot 110. However, when this port is opened, the suction to the foot is broken by atmospheric pressure entering the port.

The valve port 147 is opened and closed in timed relationship with the operation of the suction foot 110. Pivoted to the body of the valve 145 is a lever 148 which carries a closure 149 for the port 147. A spring 150 normally retains the closure seated against the valve port. In Fig. 2, the parts are shown in the positions they assume immediately after the closing of the valve port to apply suction to the foot 110. It will be remembered that the foot is raised and swung forward by the clockwise rotation of the shaft 118. Secured to this shaft is a lever 151 having an inwardly extending portion 152 which carries an adjustable screw 153 and a contactor 154. As the shaft 118 swings to cause a sheet to be fed, the lever 151 swings toward the upper end of the valve lever 148, and as the feed rolls 111 and 112 grip the sheet, the screw 153 contacts the lever 148, opening the port 147 and causing the sheet to be released from the suction foot.

When the valve closure lever 148 moves to open the valve port, a pin 155 carried thereby engages and cams upward one arm of a bell crank 156. A spring 157, interposed between the bell crank and a frame plate 57 then causes a latch portion 158 of the bell crank to engage the pin 155 and retain the valve closure 149 in an open position. On the return stroke of the foot 110, the swinging of the shaft 118 in a counter-clockwise direction, then causes the contactor 154 of the lever 151 to engage an adjustable screw 153 on the upper arm of the bell crank 156, and moves the latch portion thereof out of engagement with the port closure lever 148, closing the port and

returning the parts to the position illustrated in Fig. 2.

The pressure side of the pump is connected by a pair of conduits 161 to respective jets 160 disposed at opposite sides of the stack of sheets. As shown in Fig. 2, these jets direct air under pressure toward the sides of the uppermost sheets in the stack. The jets are positioned adjacent the forward edges of the stack and direct blasts of air beneath the forward portion of each sheet while it is being lifted by the suction foot.

Despite the precautions taken and the high efficiency of the sheet separating mechanisms above described as compared with sheet separating and feeding mechanisms now in use, it has been found that climatic conditions and other factors, particularly irregularities, blemishes or semi-porous condition of the paper sheets themselves, sometimes causes more than one sheet to be fed at a time. This has numerous disadvantages too well known in the printing art to require enumeration here. To prevent the delivery to the printing machine of superposed sheets, a gauge 18 is provided to control the operation of a diverter 19 which diverts superposed sheets from the sheet delivery mechanism as heretofore mentioned.

As shown, the gauge comprises a carriage 170 mounted for axial adjustment on a rod 176 which extends between the side plates 57. The lower end of the carriage is positioned by a second rod 177 similarly mounted in the side plates 57. The gauging member comprises a roller 180 rotatably mounted by means of anti-friction bearings 181 on a spindle 179 which is secured to and mounted between a pair of arms 182. These arms are pivotally mounted on the lower end of a bracket 183, which as will be hereinafter more fully described is adjustably supported in the carriage 170.

Mounted on the bracket 183 is a delicate electric switch 184 of a type well known at the present time as a micro-switch and which is responsive to movements of less than one thousandth of an inch. The particular switch used has not been illustrated in detail, but is of the type which makes an electrical contact consequent upon the inward movement of a plunger 187, carried by the switch.

The switch plunger 187 is operated by a pin 186, carried by the arms 182. An adjusting screw 188, carried by the bracket engages the pin 186 in a region diametrically opposite the plunger. In this way, any lost motion in the switch mechanism or between the plunger and its contactor is controlled.

In operation, the carriage 170 is adjusted axially of the rod 176 and secured in position by a set screw 189. The bracket 183 is then adjusted vertically to position the gauge roller 180 so that it contacts a single sheet. The adjusting screw 188 is set to permit contact between the roller and the single sheet without causing the operation of the switch mechanism. However, when more than one sheet passes between the gauge roller and the lower feed roll 111, the arms 182 rock about their pivot 190 and the pin 187 actuates the switch mechanism.

It will be noted from Fig. 5, that the gauge roller contacts the sheets forward of a line intersecting the axes of the feed rolls 111 and 112. This has a decided advantage in that it compensates for slight variations in the thickness of the sheets. By placing the gauge roller in advance of the feed rolls, any buckling of the sheet, which sometimes occurs immediately after the sheet

leaves such rolls, cannot affect the gauge mechanism and cause the diversion of the sheet. It has been found expedient in sheet feeding mechanisms of this general type to have the upper feed roll comprise a series of axially spaced rolls. Again, by positioning the gauge roll in advance of these upper feed rolls, buckling of the sheet between these rolls does not affect the gauge mechanism. This feature is especially advantageous when comparatively thin sheets, such as tissues, are being fed.

Vertical adjustment of the gauge roller to compensate for sheets of different thickness is made by moving the bracket 183 vertically in the carriage 170. The bracket is slidably mounted for vertical movement in ways 192 formed in the carriage, and is supported by a plunger 193 secured to the bracket by a nut 194 and which is slidable in a vertically extending bore 195 in the carriage. A knurled adjusting screw 196 passing through an opening in the top of the carriage threadingly engages the plunger and provides for its vertical adjustment. A compression spring 197, interposed between the upper end of the plunger and the top of the carriage, maintains the bracket in its lowered position and prevents damage to the mechanism. A leaf spring 198 engages the knurled head of the screw and maintains it in an adjusted position.

The upper feed rolls 112 are likewise adjustable for sheets of different thickness. As heretofore mentioned, these rolls are rotatably mounted on a shaft 200. This shaft (Fig. 3) is mounted between a pair of arms 201 which are pivotally mounted on a cross frame shaft 202. Secured to each arm 201, as at 203, is an upwardly extending threaded stud 208, which passes freely through a block 204, carried by the adjacent side plate 57, and which is engaged at its upper end by a knurled nut 205. A compression spring 206, interposed between an abutment 207 on the stud and the lower face of the block 204, resiliently maintains the arm in its lowermost position and prevents damage to the parts.

The feed rollers 111 and 112 are continuously rotated in the direction to feed the sheet forwardly by suitable means operating in timed relation with the printing machine.

The feed rolls 111 and 112 are preferably driven in timed relation with the printing machine. As indicated in Figs. 1 and 2, a driving belt 162 extends from a suitable motor driven sheave not shown over a pulley 163 (Figs. 1 and 2) on the shaft 166 of the roller 220 of the delivery mechanism hereinafter more fully described. A second sheave 165 is also tight on the shaft 166. A second drive belt 164 interconnects a sheave 165 with a sheave 167 which is drivingly secured to the lower feed roll 111 in the usual manner.

As heretofore mentioned, the detector mechanism 18 actuates a diverter plate 19 which diverts superposed sheets from the normal path of sheet travel. The sheets W as they leave the feed rolls 111 and 112, normally travel in a horizontal plate to a set of advancing rolls 220 and 221, of the delivery mechanism. A table 222-223 bridges the gap between the two sets of rolls. The section 223 of this table is pivotally mounted, as at 224, to the side frame plates 57, while the section 222 is permanently secured to such side plates.

When the switch 184 of the gauge mechanism is energized due to the detection of the superposed sheets, it completes an electrical circuit which energizes a solenoid 225, shown in Fig. 4.

The movable core 226 of this solenoid is connected by a link 227 with a flanged end of the diverter plate 223, as indicated at 228. The arrangement is such that the energization of the solenoid 225 rocks the diverter plate 223 into the position indicated by the dotted lines on Fig. 4, against the action of a spring 229. The superposed sheets, traveling in the direction of the arrow shown in Fig. 4, then pass beneath the raised end 230 of the diverter plates 223, and are diverted downward beneath the roll 220 into a suitable receptacle, indicated at 235 in Fig. 2.

When the diverter trip plate 223 is moved to the dotted line position shown in Fig. 4, it is latched in such position for the remaining portion of that cycle of operation of the feeding and separating mechanism. As the diverter plate rocks, a pin 231 carried thereby moves to the dotted line position shown in Fig. 4. The movement of the pin cams a pivoted latch 232 outward until the pin passes above the latch, whereupon a spring 233 draws the latch into the position shown in full line beneath the dotted line position of the pin 231, retaining the deflected plate 223 in its swing position. The diverter plate is pivotally mounted at 224 and is released at the end of the cycle of operation and returned to its normal position by the spring 229.

It will be noted that the various feed rolls and associated mechanisms are arranged to facilitate the feeding of either relatively long or short sheets. It will also be noted that the feed rolls 111, 112, the detector unit 18, the diverter mechanism 19 and the rolls 220, 221 of the delivery mechanism are compactly arranged. This arrangement enables the feeding of comparatively short sheets, as for instance, postal cards and the like to the printing machine at high rates of speed.

To insure the ejection of short sheets which are diverted due to the action of the detector mechanism, a supplemental feed roll 310 is rotatably mounted in the side plates 57 and surmounted by a pressure roller 314. This feed roll is driven by the belt 164 heretofore described.

The feed roll 310 enables the positioning of the diverter plate 222 some distance away from the main feed rolls 111, 112 and the detector unit roller 180, thus permitting the sheet to travel a short distance before reaching the diverter plate 222. This compensates for the time lag in the operation of the diverter plate and thereby permits the operation of the feeding mechanism at relatively high rates of speed without detracting from the effectiveness of the sheet diverting mechanism.

Figs. 1 and 2 disclose a portion of a sheet delivery mechanism for advancing the sheets which in the normal operation are fed horizontally across the diverting gate. This mechanism includes a plurality of flexible endless tapes 240, extending about the constantly driven roller 220.

As a sheet progresses across the tables 222 and 223, it passes onto the tapes 240 and is retained in contact with the tapes by a plurality of rolls 221 heretofore mentioned. The rolls are best illustrated in Fig. 1, and are rotatably mounted on a shaft 245 carried between a pair of arms 246, which are pivoted on a bar 247, extending between the side plates 57. If desired, suitable lightweight spring guides 249 mounted on the rod 247 may be used to guide the sheets into the bite of the rolls 220 and 221.

I claim:

1. In a sheet feeding mechanism, the combination of a pair of feed rolls, to and from which the sheets may be fed one at a time, means for diverting a sheet if two are fed at a time including a detector to detect the passage of multiple sheets, a switch to control the diverting means and itself controlled by the detector, means for adjusting the relation of the detector to the switch, and means for adjusting the relation of the detector to the sheet without changing the adjustment between the detector and the switch.

2. In a sheet feeding mechanism, a feed roll, means to feed sheets one at a time to said roll, a detector to detect the passage of superposed sheets to said roll, said detector comprising a body, a bracket mounted on said body and adjustable toward or from the path of the sheets, an electric switch carried by said bracket, an operating member therefor, carried by the bracket and comprising a bell crank, one arm of which coacts with said switch, a sheet contacting roller carried by the other arm of said bell crank and coacting with the feed roll to gauge the thickness of the sheet passing therebetween, and means responsive to action of the switch consequent upon the passage of superposed sheets between the roller and the feed roll to divert such superposed sheets from the normal path of travel of single sheets.

3. In a sheet feeding mechanism, the combination of a pair of feed rolls, means to feed sheets one at a time to and from the bite of the feed rolls, means for diverting a sheet if two are fed at a time including a detector adapted to coact with one of the feed rolls and be moved by the passage of multiple sheets, a bracket carrying the detector, means for adjusting the bracket, a switch carried by the bracket and adapted to control the diverting means, and means mounted on the bracket for adjusting the relation of the detector to the switch, whereby the relation of the detector to the cooperative feed roll may be changed without changing the adjustment of the detector and the switch.

4. A gauge device for a sheet feeding mechanism comprising a body provided with a vertically extending guideway, a bracket movable along the guideway, means to adjustably limit the downward movement of the bracket in the guideway, resilient means between the bracket and the body to retain the bracket in its lowered position, an electric switch carried by said bracket, an operating member therefor, carried by the bracket and comprising a bell crank, one arm of which coacts with said switch, a sheet contacting roll carried by the other arm of said bell crank and a bearing disposed between the roll and said bell crank, and relatively fixed means coacting with said roll to enable the gauging of a sheet or sheets passed between said last named means and said roll.

5. In a sheet feeding mechanism, the combination with a feed roll, of a support, a bracket adjustably carried by the support, a lever mounted on the bracket, a roller carried by the lever and adapted to coact with the feed roll, a switch mounted on the bracket and controlled by the lever, and an adjustment for the switch mounted on the bracket, whereby the adjustment of the bracket permits variable presentation of the detector roller to the feed roll without changing the adjustment of the switch.

FRANKLIN E. CURTIS.
